UNITED STATES PATENT OFFICE.

JAMES R. HARRISON, OF PEORIA, ILLINOIS, ASSIGNOR TO M. RUMELY COMPANY, OF LAPORTE, INDIANA, A CORPORATION OF INDIANA.

DESIGN FOR A CASING FOR GRAIN-WEIGHERS FOR THRESHING-MACHINES AND THE LIKE.

46,671.

Specification for Design.

Patented Nov. 24, 1914.

Application filed June 4, 1914. Serial No. 843,100. Term of patent 14 years.

To all whom it may concern:

Be it known that I, JAMES R. HARRISON, a citizen of the United States, residing at Peoria, in the county of Peoria and State of Illinois, have invented a new, original, and ornamental Design for Casings for Grain-Weighers for Threshing-Machines and the like, of which the following is a specification, reference being had to the accompanying drawing, forming part thereof, wherein is shown a perspective view of my design.

I claim:

The ornamental design for a casing for grain weighers for threshing machines and the like, as shown.

JAMES R. HARRISON.
